CONTAINER FOR VISCOUS LIQUIDS

William Henry Stokes, Allesley, near Coventry, England, and Henry Einem Hickson, Holywell, Wales, assignors to Courtaulds Limited, London, England, a British company

Application December 8, 1937, Serial No. 178,826
In Great Britain December 17, 1936

5. Claims. (Cl. 259—180)

This invention relates to an improved construction of container, adapted to receive and deliver viscous liquids. It is particularly concerned with large containers such as are used in the artificial 5 silk industry, for receiving and delivering liquids such as viscose.

In the extrusion, for example, of viscose to produce artificial filaments, viscose is supplied to the nozzles from large tanks or containers. A 10 tank may either be refilled with fresh viscose after the whole of its contents has been delivered to the nozzles, or it may be continuously supplied with fresh viscose while delivery is taking place. Since the age of the viscose has a marked 15 effect on the properties of the filamentary product obtained therefrom, it is very desirable to ensure that batches of viscose of different ages are not irregularly mixed together. We have found when using the first of the aforementioned methods 20 of refilling a tank and delivery therefrom, that there is a tendency for the fresh viscose to stream from the supply tube into the tank in such a manner that on emptying the tank, the order of removal of the viscose is different from the order 25 of entry. In other words, batches of viscose of different ages are irregularly mixed together:

For this reason, the production of absolutely 30 uniform threads is not possible. Similarly, we have found when using the second of the methods mentioned above, that fresh viscose tends to 35 stream from the supply tube directly to the delivery tube leaving older viscose adhering to and in the vicinity of the sides and corners of the tank. In this case also the obtaining of uniform products has been rendered more difficult by the 40 consequent irregular mixing together of viscose batches of different ages.

The object of the present invention is to avoid 45 the above mentioned difficulties by ensuring that the viscose or other liquid streams into the tank in proper order, and on emptying, flows away in the same order as it entered.

We have now found that this object can be 50 attained by using a tank or container within which suitably shaped bodies are placed, one adjacent to the mouth of the supply tube, in the path of the liquid entering, and one adjacent to the delivery tube in the path of the liquid leaving the tank.

The type of container with which the invention 55 is particularly concerned, comprises a vertical cylindrical tank, preferably having conical or the like shaped ends, with supply and delivery tubes entering and leaving the tank at the centres of the upper and lower ends respectively.

The invention however, is not limited to tanks of this shape. The walls of the tank may be other than cylindrical, for example, hexagonal or octagonal while the ends may be, for example, dome shaped or flat. The top end may even be 5 left open.

With a cylindrical tank with conical or the like shaped ends two of the aforesaid bodies may be used each having the shape of two cones or cone-like bodies placed and united base to base. The 10 diameters of the bases are equal to one another, but somewhat less than that of the tank. The contour of the lower cone of the lower body corresponds approximately to that of the lower end 15 of the tank. The double conical or the like shaped bodies are arranged in the tank so that the lower cone of one, fits into the cone-shaped lower end, and the upper cone of the other fits into the cone-shaped upper end of the cylindrical tank. Each double cone-shaped body, although 20 adjacent and fitting into the cone-shaped end of the cylinder is spaced apart therefrom, so that at each end of the tank, there is a regular annular space between the body and the tank end. The upper cone of the lower body and the lower 25 cone of the upper body project upwardly and downwardly respectively into the tank. Their dimensions are such as to prevent the formation of areas where liquid can stagnate untouched by the flow of the main body of liquid.

While it is essential, according to the invention, that the contours of the lower body should in the part adjacent to the lower end of the tank follow closely the contours of the said end, the upper part of the upper body is preferably conical, dome-shaped or the like and does not necessarily correspond to the shape of the top end of the tank. It is placed with its apex or top-most point immediately below the liquid entry tube so as to spread the liquid evenly round the periphery 35 of the tank. The bodies should in general not be much smaller in width than the tank. For example, when using cone-shaped bodies in a cylindrical tank for storing viscose the diameters 40 of the bodies should not be less than half that of the interior of the tank. They may be solid or hollow, and may be made of any material which is not acted upon by the liquid to be used in the containers. If the liquid is viscose, they 45 may be made, for example, of a resistant metal. The upper and lower bodies may be connected if desired by means of rods or other suitable means. They are held in position inside the tank, by means, for example, of brackets attached to the 50 walls or ends of the tank.

The accompanying diagrammatic drawing illustrates a tank or container according to the invention in which the cylindrical tank 1 is provided with a supply tube 2 and an exit tube 3 at the centres of its upper and lower ends respectively. The lower end 5 is conical in shape and the upper end 6 slopes up to a non-central vent-pipe 4 through which any gases given off from the liquid may be withdrawn. The bodies 7 and 8, rigidly connected by a rod or tube 9 are placed inside the tank. The lower cone-shaped body 8 fits into the conical end 5 of the tank and is spaced apart therefrom by lugs 10 which also assist in holding the inserted bodies firmly in position.

Liquid enters through the supply tube 2, flows down between the upper cone of the body 7, and the tank walls, and leaves through the exit tube 3 via the annular space between the body 8 and the tank end 5. A streamline effect is created by the elimination of corners where stagnation could occur, and the liquid is caused to leave the tank in substantially the same order as it enters.

What we claim is:

1. Apparatus for receiving a viscous liquid and delivering it in approximately the same order as it is received, which comprises a tank of uniform interior cross sectional shape with a lower end sloping in all parts to an exit pipe and two fixed bodies inside but spaced apart from the tank, one at the upper end of the tank in the path of the entering liquid of cross sectional shape at its widest part similar to but smaller than that of the tank interior, and the other at the lower end of the tank adjacent the liquid exit, both the upper and lower parts of each body being tapered inwardly away from the tank interior in a streamline effect of similar but decreasing cross sectional shape and the lower part of the lower body being of similar shape to the lower end of the tank.

2. Apparatus for receiving a viscous liquid and delivering it in approximately the same order as it is received, which comprises a vertical cylindrical tank having a conical lower end with a supply tube at the centre of the upper end and a delivery tube at the centre of the lower end, and two fixed bodies inside but spaced apart from the tank, one in the path of the entering liquid of cross sectional shape at its widest part similar to but smaller than that of the tank interior and the other at the lower end of the tank adjacent to the liquid exit, both the upper and lower parts of each body being tapered inwardly away from the tank interior in a streamline effect of similar but decreasing cross sectional shape and the lower part of the lower body being of similar shape to the lower end of the tank.

3. Apparatus for receiving a viscous liquid and delivering it in approximately the same order as it is received, which comprises a tank of uniform interior cross sectional shape with an upper end having a liquid supply tube therein and with a lower end sloping in all parts to an exit pipe and two fixed rigidly connected bodies each comprising two cone-like portions united base to base, the said bases being equal to each other but less than the tank in diameter, inserted in the said tank in such a position that the lower cone like portion of the lower body fits into but is spaced apart from the lower end of the tank and the apex of the upper portion of the upper body is immediately beneath the liquid supply tube in the upper end of the tank.

4. Apparatus for receiving a viscous liquid and delivering it in approximately the same order as it is received, which comprises a vertical cylindrical tank having a conical lower end with a supply tube at the center of the upper end and a delivery tube at the center of the lower end and two fixed rigidly connected bodies each comprising two con-like portions united base to base, the said bases being equal to each other but less than the tank in diameter, inserted in the said tank in such a position that the lower cone-like portion of one body fits into but is spaced apart from the lower end of the tank and the apex of the upper cone-like portion of the other body is immediately beneath the liquid supply tube in the upper end of the tank.

5. Apparatus for receiving a viscous liquid and delivering it in approximately the same order as it is received, comprising a tank having an upper end provided with an inlet and a lower end provided with an exit and sloping in all parts toward said exit, said tank being of constant cross sectional shape between said ends, in combination with two fixed bodies inside but spaced apart from said tank, one near said upper end in the path of the entering liquid of cross sectional shape at its widest part similar to but smaller than that of the tank interior, thereby defining with the tank interior a throat surrounding said body and of uniform width, and the other at the lower end of the tank adjacent the liquid exit similarly forming a lower throat surrounding the same, the lower part of the upper body and the upper part of the lower body tapering inward away from said tank and from each throat toward the other, thereby forming a liquid space surrounding said bodies and extending between said throats but of materially greater cross sectional area therebetween.
